UNITED STATES PATENT OFFICE.

JOHN F. OTIS, OF OSWEGO, NEW YORK.

STEAM-GENERATOR.

1,355,687.

Specification of Letters Patent. Patented Oct. 12, 1920.

Original application filed April 11, 1914, Serial No. 831,137. Divided and this application filed January 13, 1917. Serial No. 142,215.

To all whom it may concern:

Be it known that I, JOHN F. OTIS, a citizen of the United States of America, and resident of Oswego, Oswego county, and 5 State of New York, have invented certain new and useful Improvements in and Relating to Steam-Generators, of which the following is a specification, this application being a division of my application filed 10 April 11, 1914, Se. No. 831,137, for steam-generators.

This invention relates to certain improvements in steam generators; and the objects and nature of the invention will be readily 15 understood by those skilled in the art in the light of the following explanation of the accompanying drawings illustrating what I now believe to be the preferred embodiments and mechanical expressions of my 20 invention from among other formations, arrangements and constructions within the spirit and scope of the invention.

The object of the invention is to arrange a superheater as close as possible to the 25 upper surface of the top flue sheet and within the flame issuing from the fire tubes to utilize the otherwise waste heat for superheating the steam and to maintain the superheater within a zone of the highest possible 30 temperature; and to so form, construct and support the superheater as to gain the greatest possible advantage from this high temperature without obstructing and disturbing the draft through and without causing 35 back pressure within said tubes and without excessive deposits on the superheater and sheet and consequent difficulties; and to so form the superheater both internally and externally as to subdivide and distribute the 40 steam in a manner to gain the full advantage of said high temperature in superheating the steam and at the same time to produce a superheater of extreme simplicity and strength against the expansive force of the steam.

45 With these objects in view, the superheater of my invention is characterized in whole or in part by a casting or other body so formed that it can be located close to the top tube sheet of the boiler without obstructing the draft through the fire tubes and so formed and balanced with respect to a central vertical bottom steam inlet that the superheater can be supported and supplied with steam by means affording no obstruction to the draft; said superheater embody-

ing uniformly spaced and distributed long rounded comparatively small tube-like members that are exceedingly strong against internal pressure by reason of their rounded formation and that do not obstruct the draft 60 because of their small diameter and rounded formation and that are internally formed to distribute the steam from said inlet in long small outgoing streams and corresponding parallel long small return streams leading to a single central steam outlet, with abrupt transverse edges exposed to said steam and traversed thereby at the junctions between the outgoing and return streams of steam. 70

Referring to the accompanying drawings;—

Figure 1, is a vertical section through a portion of a steam generating apparatus built in accordance with my invention. 75

Fig. 2, is a horizontal section on the line 2—2, Fig. 1.

Fig. 3, is a section on the line 3—3, Fig. 2.

In the particular example illustrated, I 80 show part of an upright steam generator having upright inclosing shell or wall 2, and horizontal crown or top flue sheet 1, in which the upper ends of a multiplicity of vertical fire tubes 7, are secured and through which 85 they open into the combustion chamber above said flue sheet. These fire tubes extend through the steam and water spaces within the boiler shell and at their lower ends are secured in a suitable bottom head 90 or flue sheet (not shown) and extend therethrough and open into the fire box or chamber of the boiler to carry off the burning gases and smoke and deliver them into the combustion chamber above flue sheet 1 after 95 subjecting the water and steam to the heat generated thereby.

These fire tubes pass through a dry or separator plate 16, spanning the steam space of the boiler a short distance below flue sheet 100 1, and suitably secured to and carried by shell 1. The plate 16 fits the inner surface of shell 2 to preferably form a steam tight joint, and the plate is formed with perforations for the passage of the fire tubes, the plate 105 being otherwise imperforate. The perforations closely receive the fire tubes to form restricted thin spaces between the surfaces of the fire tubes and the edges of the plate surrounding the tubes through which the steam 110

passes in films. The steam is more or less superheated in passing through these perforations along the hot surfaces of the steam and moisture is evaporated therefrom. The 5 plate 16 becomes highly heated and tends to flash water carried by the steam into vapor, and furthermore, the edges of the plate at the holes therethrough will tend to catch water carried by the steam and separate the 10 same from the steam.

I provide a combustion or hot gas chamber at the top of the upper flue sheet 1, and into which the flues or tubes 7 will discharge the hot or burning products from the combustion 15 chamber. For instance, I show an upwardly extending hood 18 mounted on the upper end of the boiler and at the upper end having a suitable outlet or discharge 19. I provide means for passing the steam from 20 the boiler through the combustion chamber within this hood for the purpose of separating all water from the steam and thoroughly superheating the steam before it passes off to perform its work whether for heating or 25 power purposes.

The boiler is provided with a vertical steam outlet pipe or nipple 20 opening into the steam space of the boiler approximately through the center of the flue sheet 1, and this nipple rises from said flue sheet and opens into the center of a combined separator and superheater arranged horizontally within the hood 18, and immediately above the flue sheet 1, and the upper ends of the 30 fire tubes. This superheater is formed with a central top steam outlet or discharge receiving the pipe 21 passing through the hood and exposed to the heat therein and extending to the exterior of the hood. This pipe 35 constitutes the steam offtake or supply through which the steam is supplied for performing the work desired and any suitable means can be provided for controlling the passage of steam therefrom.

40 The superheater preferably consists of several longitudinally elongated hollow arms or bodies 22, radiating from a common hollow center or hub 23, and the interiors of the hub and arms are spanned by an imperforate baffling plate or diaphragm 24 preferably located centrally or midway between the bottom and bottom walls of the arms and hub. The interiors of the arms 22 open into the interior of the hub and the arms are 45 otherwise imperforate and the baffling plate spans the hub dividing the interior thereof into a bottom steam inlet space receiving the steam pipe 20 and a top steam outlet space receiving outlet pipe 21. The plate 50 extends from the hub longitudinally within the arms but terminates short of the outer ends of the arms so that each arm has a longitudinal steam passage leading outwardly from the inlet steam space of the hub to a 55 vertical steam port or passage 25 beyond

the end of the baffling plate and at the outer end of the arm, and a longitudinal return steam passage above the baffling plate and from port 25 to the upper steam space of the hub.

70 The steam enters the superheater vertically through pipe 20, and impinges directly against the baffle plate and is then divided into outwardly flowing streams in the several arms and also return flowing streams in 75 said arms, and is thereby subjected to the intense heat under the hood and is thoroughly superheated.

The surfaces and edges of the baffling plate will tend to separate all water from the 80 steam and vaporize and superheat the same. The superheater is arranged directly above the fire tubes within the zone and influence of the hot burning gases issuing from said tubes and the heat of such combustion is 85 thus fully utilized in superheating the steam sub-divided as it is within and by the superheater.

The superheater with its baffling plate is 90 preferably cast in one piece or otherwise formed integral of suitable metal.

It is evident that various changes, modifications and variations might be resorted to without departing from the spirit and scope of my invention and hence I do not wish to 95 limit myself to the exact disclosures hereof.

What I claim is:—

1. A superheater constructed for location close to the upper surface of the top tube sheet of a vertical fire tube boiler and to 100 be supported from said sheet by a central vertical nipple forming the steam passage from the boiler to the superheater; said superheater consisting of a central hollow hub having horizontally-elongated hollow 105 arms radiating therefrom and opening therewith and supported thereby; said arms being uniformly spaced, closed at their outer ends, small in diameter and substantially cylindrical; the hub and arms being internally 110 sub-divided into upper and lower steam chambers and small elongated passages, the passages of each arm communicating at the outer end of the arm, said hub having a central vertical bottom steam supply opening 115 and a central vertical top steam outlet opening.

2. A vertical fire tube boiler having a steam-outlet from its top tube sheet, and a superheater arranged horizontally over 120 said tube sheet and receiving the steam from said outlet; said superheater composed of a spider-like hollow body formed to avoid obstructing the draft from the fire tubes and internally formed to provide uniformly distributed small elongated outgoing steam passages or the steam received from said outlet and uniformly distributed small elongated return passages for the steam from 125 said outgoing passages and having a steam 130

discharge receiving the steam from said several return passages.

3. A superheater having a central vertical bottom steam inlet and a central vertical top steam outlet and embodying uniformly spaced and distributed tube-like longitudinally-elongated arms internally formed to provide long small outgoing steam passages for the steam from said inlet and corre-

sponding small long return steam passages 10 from and parallel with said outgoing passages and delivering the steam to said outlet, abrupt transverse edges being provided and exposed to the steam at the junctions between the outgoing and return passages.

Signed.

JOHN F. OTIS.
